DESIGN FOR A COMBINATION STOOL AND COFFEE TABLE

Ferdinand Kramer, Portchester, N. Y., assignor to Allied Purchasing Corporation, New York, N. Y., a corporation of New York, and Fred V. Gerstel, New York, Ferdinand Kramer, Portchester, and Paul M. Mazur, New York, N. Y.

Application June 16, 1943, Serial No. 110,464

Term of patent 14 years

To all whom it may concern:

Be it known that I, Ferdinand Kramer, a citizen of no country but having declared my intention of becoming a citizen of the United States of America and a resident of Portchester, county of Westchester, State of New York, have invented a new, original, and ornamental Design for a Combination Stool and Coffee Table, of which the following is a specification, reference being had to the accompanying drawing, forming a part thereof.

In the drawing:

Fig. 1 is a perspective view of a combination stool and coffee table embodying my design, with the table leaves open to form a coffee table; and

Fig. 2 is a perspective view of the combination stool and coffee table, with the table leaves turned in to form a stool.

I claim:

The ornamental design for a combination stool and coffee table, as shown.

FERDINAND KRAMER.
